(57) **CLAIM**

The ornamental design for a dryer ball holder, as shown and described.

DESCRIPTION

FIG. 1 is a front perspective view of a dryer ball holder, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the dryer ball holder, which form no part of the claimed design. The "Ants Voice" forming part of the claimed design disclosure is a registered trademark of the Ants Voice.
